UNITED STATES PATENT OFFICE.

ZENAS B. OSGOOD, OF PORTLAND, MAINE, ASSIGNEE OF ONE-HALF TO
EDWARD C. PLUMMER, OF SOUTH PORTLAND, MAINE.

DESIGN FOR A FORK, EGG-HOLDER, AND BEATER.

SPECIFICATION forming part of Design No. 32,785, dated June 5, 1900.

Application filed April 18, 1900. Serial No. 13,401. Term of patent 3 $\frac{1}{2}$ years.

To all whom it may concern:

Be it known that I, ZENAS B. OSGOOD, a citizen of the United States, residing at Portland, in the county of Cumberland and State of Maine, have invented a new and original Design for a Fork, Egg-Holder, and Beater, of which the following is a specification.

This invention relates to a new and original design for a fork, egg-holder, and beater; and the essential feature resides in an intermediate twisted handle with one extremity formed with a plurality of loops of elliptical contour having a deflection in reverse directions and the opposite extremity having parallel members which are curved in part.

In the drawings, Figure 1 is a perspective view of a fork, egg holder, and beater embodying the features of the design. Fig. 2 is a side elevation of the same.

The intermediate handle portion 1 is regularly twisted and has at one extremity two divergent curved members 2 of elliptical contour, which cross each other at their outer por-

tions and continue into secondary smaller elliptical bends 3, which terminate in a centrally-disposed ellipse 4. The secondary elliptical bends 3 stand outward from the plane of the members 2 and at an angle to the latter, and the ellipse 4 extends between the bends 3 and has a reverse angular direction. 25 The opposite extremity of the utensil has parallel arms 5, which are straight and terminate in parallel concavo-convex bends 6 and in the shape of a fork with the said additional curved configuration. 30

Having thus described the invention, what is claimed as new is—

The design for a fork, egg-holder and beater, herein shown and described.

In testimony that I claim the foregoing as my own I have hereto affixed my signature in the presence of two witnesses.

ZENAS B. OSGOOD.
